ATTORNEY

UNITED STATES PATENT OFFICE.

DUDLEY C. BENTON, OF SAN DIEGO, CALIFORNIA.

HOOK AND EYE.

1,380,519.

Specification of Letters Patent. Patented June 7, 1921.

Application filed August 19, 1920. Serial No. 404,547.

To all whom it may concern:

Be it known that I, DUDLEY C. BENTON, a citizen of the United States, residing at San Diego, in the county of San Diego and State 5 of California, have invented a certain new and useful Hook and Eye, of which the following is a specification.

My invention relates to a hook and eye for fastening two parts of a garment or the like 10 together and the objects of my invention are: first, to provide a hook and eye fastener, the members of which are in substantially the same plane whether connected or disconnected so that the garment on which they 15 are attached may be ironed without bending or flattening the members; second, to provide a hook and eye fastener of this class which is easily hooked and unhooked but when hooked together will remain in hooked position; third, to provide a new and novelly 20 constructed hook and eye fastener; fourth, to provide a hook and eye of this class which is very simple and economical of construction, durable, easy to attach to the garment 25 and will not readily deteriorate or get out of order.

With these and other objects in view as will appear hereinafter my invention consists of certain novel features of construction, 30 combination and arrangement of parts and portions as will be hereinafter described in detail and particularly set forth in the appended claims reference being had to the accompanying drawings and to the characters of reference thereon which form a part 35 of this application in which:

Figure 1 is an elevational view, on an enlarged scale, of my hook and eye fastener in its hooked position on a garment and 40 showing portions of the garment broken away to facilitate the illustration; Fig. 2 is an edge elevational view thereof and Fig. 3 is a sectional view through 3-3 of Fig. 1.

Similar characters of reference refer to 45 similar parts and portions throughout the several views of the drawings.

The hook member consists of the loop portions 1 and 2, straight portions 3 and 4, bends 5 and 6 and tongue portions 7 and 8, while 50 the eye member consists of the loop members 9 and 10, straight portions 11 and 12, bends 13 and 14 and cross curve portion 15.

The loop members 1 and 2 are formed for 55 securing the devices to the garment and the members extended forming the straight portions 3 and 4, then the curved portions 5 and

6, then extending forwardly crossing each other at the point 7^a, then diverging to points 7^b and 8^b, then converging to a short turn 8^c, the end 60 of the hook member is positioned considerably in advance of the loop members 2. It will also be noted that where the members 7 and 8 cross each other they are flattened and bent over each other as shown best in 65 Figs. 2 and 3 of the drawings and that the lower side of the loops 5 and 6 are also flattened and bent around the members 11 and 12 of the eye member. The eye member is of the conventional form, except that 70 where the bends 5 and 6 cross it, when they are hooked together, it is provided with bent flattened portions as shown best in Figs. 2 and 3 of the drawings and the curved portion 15 on the side engaging the member 8 is also 75 bent and flattened so that the two members when hooked together or when separate form hook and eye members which are nearly flat and not subject to bending or breaking when ironed as is the ordinary hook and that both 80 of the members lie flat on the garment when hooked or unhooked.

Though I have shown and described a particular construction, combination and arrangement of parts and portions I do not 85 wish to be limited to this particular construction, combination and arrangement but desire to include in the purview of my invention the construction, combination and arrangement substantially as set forth in the 90 appended claims.

Having thus described my invention what I claim as new and desire to secure by Letters Patent is:

1. A hook and eye fastener, including supporting members and a tongue member in substantial alignment therewith intermediate the supporting members formed by an integrally folded member extending some distance past the supports and crossed on the 100 opposite sides from said supports and an eye member adapted to engage said tongue member and provided with short bends and flattened portions at their engaging points when connected together. 105

2. A hook and eye fastener, including a spring wire member folded intermediate its ends to a close bend, then spread slightly, diverging for some distance, then converging and crossing, then bent backwardly and 110 formed into a loop for a support and an eye member adapted to engage and pass over

the closely bent point in U form provided with loops for supporting the same.

3. A hook and eye fastener, including a spring wire member folded intermediate its 5 ends to a close bend, then spread slightly, diverging for some distance, then converging and crossing, then bent backwardly and formed into a loop for a support, and an eye member adapted to engage and pass over

the closely bent point in U form provided 10 with loops for supporting the same, each of said members being provided with short flattened bends at the points of engagement when hooked together.

In testimony whereof, I have hereunto set 15 my hand at San Diego, California, this 14th day of August, 1920.

DUDLEY C. BENTON.
